United States Patent Office.

HENRY WILLGOHS, OF NEW YORK, N. Y.

Letters Patent No. 97,845, dated December 14, 1869.

IMPROVEMENT IN MAKING PIANO-LEGS.

The Schedule referred to in these Letters Patent and making part of the same.

To all whom it may concern:

Be it known that I, HENRY WILLGOHS, of the city and county of New York, and State of New York, have invented certain new and useful Improvements in the Manufacture of Carved Piano-Legs; and I do hereby declare that the following is a full and exact description thereof.

Much of the labor of carving piano-legs lies in the production of the flat surfaces of ground-work between the ornamental projecting parts, scrolls, &c. My invention greatly reduces this labor.

The nature of my invention consists in applying to the external face or rounded angle, at the outer corner of the leg, a piece diagonally fitted on a diagonally-prepared inner face, which cuts obliquely across and through the material, and in carving the corner-piece so applied, so that it harmonizes with the work on other pieces glued as usual on the sides, as will be fully set forth below.

It also consists, in connection with the above, in a peculiar means of reducing the labor of carving such corner-piece.

I will proceed to describe what I consider the best means of carrying out my invention.

The accompanying drawings form a part of this specification.

Figure 1 is a plan view of a complete leg.

Figure 2 is a face view of the corner-piece, which is peculiarly prepared, and glued on obliquely to the other parts.

Figure 3 is a section of the corner-piece, on the line S S, before being glued in place.

Figure 4 is a section on the same line, after the gluing and carving.

(The remaining figures aid in explaining the construction of the entire leg. They are plan views on a small scale.)

Figure 5 shows the block which forms the foundation for the leg, after two pieces, properly outlined, have been glued thereon, and before any preparation has been made to produce the rounded corner.

Figure 6 shows the same, after a large piece has been sawed from the corner, and the surface planed to receive the corner-piece.

Figure 7 shows the same, after the corner-piece has been glued on, but before the carving has been effected.

I take a block of wood, A, sawed or otherwise reduced approximately to the desired form, but smaller than would be required by the old method, and finish two flat faces, $a^1 a^2$, by planing. The planes thus produced lie at right angles to each other, and correspond to the two faces of a rectangular piano.

I perfect these surfaces by planing, and glue thereon pieces B and C, which have been previously sawed

to the proper outline for the scroll-work, vine-work, &c., on these flat surfaces.

This provides for the two flat surfaces, with carved work raised thereon. Taste or fashion requires such surfaces, and, also, a rounded surface at the corner.

The production of these rounded surfaces in connection with the flat, with carved work projecting over the whole, involves a difficulty which my invention provides for surmounting, with little labor or expense.

I saw off the angle of the compound mass, and plane the surface, and thus produce the new surface a^3 , standing oblique to both the others, $a^1 a^2$.

Upon this surface, I glue a third piece of lumber, D. I cut the corner-piece D by a narrow jig-saw, along the lines where an abrupt cut is required.

These lines are indicated by d, in fig. 2, and are extended so far as to nearly divide the piece D, but not quite.

It will be obvious that when the piece D is firmly glued upon the oblique plane surface on which it is fixed, all of the parts are very strongly supported by the glue, and the wood might be entirely divided along its lines d without detriment; but, in order to operate conveniently in attaching the parts, I prefer to leave the piece D entire, so that it may be handled as a single piece.

The lines, where the piece D is nearly divided, aid very greatly in reducing the labor of carving, because I thereby avoid the necessity of sinking the offsets at the lower edges of the leaves or folds, scrolls, &c. Instead of cutting both sides of the deep channels by hand, the saw-kerf forms one side, and it is necessary to form only the other and more gradually-sloping side by hand.

My invention is most valuable in working out those designs in which very little ground is allowed to appear near the corner of the leg, but when the pattern or design is such that a small portion of the ground-work appears near the corner, it is produced by the old means; that is to say, it is sunk and finished by hand, so as to give the proper rounded contour.

When necessary, the rounding of the corner may be carried a little way upon the flat face, $a^1 a^2$, of the original block A.

It will be understood that the labor of producing the rounded ground-work of the corner in this manner is precisely the same as was required on that portion of the surface by the old method of carving piano-legs, but my invention economizes labor very greatly in effecting all the other operations.

The saw-kerfs d are never visible, because piano-legs are only viewed from above, and because these narrow cuts are close up under the overhanging or projecting parts.

I am aware that scrolls, cut by jig-saw to the outline required for carved work, have been already glued upon plane surfaces. I glue them upon the plane surfaces a^1 and a^2 , to be afterward carved. This I do not claim, and it will not produce a carved piano-leg, with a rounded corner, without the aid of invention.

My invention allows such to be produced in greater perfection than ever before, and at a cost below those made in any previously-known way.

I claim a piano-leg, when constructed substantially in the manner herein shown and described.

In testimony whereof, I have hereunto set my name, in presence of two subscribing witnesses.

HENRY WILLGOHS.
